UNITED STATES PATENT OFFICE.

HENRY S. GRACE, OF SAN FRANCISCO, CALIFORNIA, ASSIGNOR OF ONE-HALF TO
JOHN B. ACTON, OF SAN FRANCISCO, CALIFORNIA.

MULTIPLE SPRING.

1,125,016.

Specification of Letters Patent.

Patented Jan. 12, 1915.

Original application filed February 5, 1913, Serial No. 746,363. Divided and this application filed August 4, 1913. Serial No. 782,967.

To all whom it may concern:

Be it known that I, HENRY S. GRACE, a citizen of the United States, residing in the city and county of San Francisco, State of California, have invented certain new and useful Improvements in Multiple Springs, of which the following is a specification.

My invention relates to springs for use in resilient wheels, or in other situations, for instance, for supporting floors or other bodies which it is desired to provide with a certain amount of resilience, and it may be applied to car platforms, the floors of cattle cars, and other situations. The form of spring is disclosed substantially in application for Letters Patent filed by me in the United States Patent Office, February 5, 1913, Serial No. 746,363.

The invention consists in the features of construction and arrangement of parts hereinafter described and particularly pointed out in the claim.

In the accompanying drawings, Figure 1 is a perspective view of one unit or member of the spring. Fig. 2 is a perspective view showing the number of units assembled to make up the complete spring, and Fig. 3 is an edge or side view of several units indicating their relative positions when assembled to form the spring though said units are separated from each other for clearness of illustration.

As shown in Fig. 1, the spring unit consists of a leaf of metal bent into a general bow shape with its ends turned outwardly and curved slightly reversely to the curved bow portion at 1. The end portions are also thin or tapered down at 2 to an edge.

Fig. 2 represents a number of units assembled to form the spring, and it will be observed that these units are staggered in relation to each other, the lowermost units terminating at the point A, where their thin edges overlap, and the next unit at this

point above the lowermost unit has its bow portion in line with the point A, while its end portions terminate above the bow portions of the lowermost units and here overlap the ends of other units, and the bow portions of these last mentioned units extend past and overlap the end portions of the lowermost units. In other words, the spring is made up of a number of units like that shown in Fig. 1, some arranged with their bow portions directed downwardly and others with their bow portions directed upwardly, the ends of adjacent units overlapping each other and the bow portion of one unit extending past or lying adjacent to the overlapping ends of the units above or below.

By the construction illustrated a compact spring is provided and one in which the overlapping ends will have a certain amount of sliding movement, one on the other, without necessitating the employment of any sections other than a multiplication of the standard unit and not requiring clearance spaces between the ends of the units. The whole spring is made up of a number of like units overlapping at certain points and having their main bow portions directed differently.

I claim as my invention:

A spring of regular undulatory shape comprising a series of units, each unit having a main bow portion and ends curving reversely to the main bow portion, each projection and depression of said undulatory spring being composed of a bow portion and adjacent overlapping ends of said units arranged alternately.

In testimony whereof, I affix my signature in presence of two witnesses.

HENRY S. GRACE.
